UNITED STATES PATENT OFFICE.

SIMEON F. PIERCE, OF ST. PAUL, MINNESOTA.

LIQUID-HYDROCARBON GENERATOR.

1,135,136.

Specification of Letters Patent. Patented Apr. 13, 1915.

Application filed July 5, 1913. Serial No. 777,542.

To all whom it may concern:

Be it known that I, SIMEON F. PIERCE, a citizen of the United States, residing at St. Paul, in the county of Ramsey and State of Minnesota, have invented certain new and useful Improvements in Liquid-Hydrocarbon Generators, of which the following is a specification.

My invention relates to improvements in generators for generating gas from heavy hydro-carbon liquids, as kerosene, its object being particularly to provide a construction in which heavy hydro-carbon liquid, such as kerosene, are generated with the same effectiveness as the lighter liquids, such as gasoline, are generated in the ordinary constructions.

In carrying out my invention I employ, as shown, a double generator, heated in operation by a sub-flame, the hydro-carbon liquid being vaporized before passing into the generators. I also preferably employ means for pulverizing the contained hard carbon to fine particles to prevent blocking of the passages, together with other coöperating features for bringing about the complete generating of the gas and maintaining a constant flame of maximum efficiency.

To this end the invention consists in the features of construction, combination, and arrangement of parts hereinafter described and claimed.

In the accompanying drawings forming part of this specification, Figure 1 is a side elevation of a street lamp, broken away, and fitted with my invention; Fig. 2 is a vertical section of my improved generator; Fig. 3 is a top view of the same; Fig. 4 is a section on line $x-x$ of Fig. 2; Fig. 5 is a section on line $y-y$ of Fig. 2; Fig. 6 is a section on line $z-z$ of Fig. 2; Fig. 7 is a detail of the end of the valve needle; and Fig. 8 is a sectional view through the needle valve orifice plug.

Referring to the drawings, A represents the generator casing of a burner embodying my features of invention. The generator is formed with a central mixing tube 2. A plug 3 is inset in the bottom of the tube 2 and is formed with a jet orifice 4, a needle valve 5 having screw threaded support in the bottom of the burner to extend into said orifice, as shown in Fig. 2.

The mixing tube is open at its lower end to the outer air, and is connected with a source of fuel supply through the medium

of the following parts: 7 represents an inlet tube for the hydro-carbon, a vaporizing chamber 8 being shown supported upon the outlet end of the tube. The chamber 8 is 60 filled with movable parts 9, as shot, for the purpose hereinafter more particularly pointed out. The chamber 8 at its upper end 10 is adapted to be detachably connected with the inlet port 11 of the generator chamber 65 12, said chamber extending around a portion of the mixing tube 2. The generating chamber 12 is connected by a downwardly and laterally extending conduit 13 with a second generating chamber 14 extending around 70 the lower end of the mixing tube, the lower generating chamber 14 at its lower side being connected by a conduit 15 with the jet orifice 4. The chambers 12 and 14 constitute spaced generators extending around the 75 central mixing tube 2. The generators 12 and 14, as shown, are preferably filled with movable parts, as the shot 16. The casing A is shown constructed with an open top tube 17 extending upwardly outside of the mixing tube 2, a plurality of sub-flame openings 18 being formed through the wall or casing between the upper end of the mixing tube and the outer upwardly projecting tube 17. The mixing tube 2 is formed with an upwardly extending portion 19.

In carrying out my invention I provide a gallery 20 fitted, as shown, over the outer tube 17, the gallery having a downwardly concaved top and being formed in said top 90 with a central opening 21 of less diameter than the mixing tube, i. e. the tube 2 and its extension 19. A suitable mantle 22 may be fitted over the gallery, as shown, any well known form of support, as the support 23, 95 being employed. The support 23 includes a screening 29 standing above the gallery and supporting a central plate 30 standing above the opening 21.

In the drawings, I show my generator arranged in connection with an ordinary street lamp, the generator being supported from the supply pipe 24 leading downwardly from the supply chamber 25 arranged within the framework of the lamp 26. The lamp 100 26 may be of any well known construction.

My invention is designed particularly for efficiently utilizing hydro-carbon liquids as kerosene in sub-flame generators, thus saving the heavier expense of using lighter 110 hydro-carbons as gasoline.

In use, the burner, including the gener-

ator chambers 12 and 14, are first thoroughly heated as by a torch. While thus heated communication with the source of fuel supply is established, as by means of the hand valve 27. The hydro-carbon liquids pass from the inlet pipe into the vaporizer 8 wherein it is vaporized, the vapor passing therefrom into the upper generating chamber 12. As shown in Fig. 2, the outlet opening for the vaporizer stands in the upper end thereof, allowing the heavy impurities in the oil to settle. The fuel is partly gasified in the upper generating chamber 12 and passes through the conduit 13 to the lower generating chamber 14, wherein the gasification is completed. From the lower chamber 14 the gas passes through the conduit 15 and orifice 4 to the mixing tube 2. In the mixing tube the gas is mixed with the air which is drawn in through the side openings 28 in the lower end of the mixing tube, the mixed air and gas passing through the upper end of the mixing tube against the top of the gallery 25 and through the central opening in the gallery top against the plate 30. The gas passing through the central opening in the gallery top is lighted within the mantle to bring about the incandescence of the mantle 30 in the ordinary manner. A portion of the gas is deflected by the gallery top and plate 30 downwardly between the top of the mixing tube and the outer tube 17 passing through the sub-flame openings 18, being ignited as they pass through the openings 18 to form the sub-flames. As indicated in Fig. 2, the sub-flames strike against the top of the lower generating chamber 14 and are deflected back against the upper generating chamber 12, thus thoroughly heating both generating chambers to bring about the double generation necessary in carrying out my invention. By the combination of the double generator with the inclosed top gallery and the upwardly extending mixing tube the sub-flame is produced at a point particularly close to the needle without igniting the gas entering the mixing tube from the needle orifice. The lower generator chamber, as illustrated in Fig. 2, constitutes a partition between the sub-flame and needle orifice.

The sub-flame, in addition to heating the double generator, heats the vaporizing chamber 8 and the contained balls 9 as well as the balls within the generating chamber. The balls 9 and the balls 16 within the generating chambers are kept in a state of agitation by the boiling of the hydro-carbon and generating of the gas, pulverizing any hard carbon preventing blocking of the passages.

By replacing the mantle shown in the drawings with devices for cooking or heating, my generator may be equally well

utilized for those purposes. I secure by the features of construction shown a generator in which heavy and relatively cheap hydro-carbon liquids, as kerosene, may be as efficiently used as the higher priced lighter 70 carbon liquids as gasoline.

For the purpose of steadyng the sub-flame as well as the flame within the mantle I preferably provide the trap partition 31 extending downwardly and outwardly from the top of the mixing tube and partly spanning the passage between the mixing tube and gallery, as indicated in Fig. 2.

I claim as my invention:

1. A burner of the class described comprising a central mixing tube, a gallery surrounding the upper portion of said mixing tube and spaced therefrom, said burner being formed with downwardly directed sub-flame orifices intermediate of the gallery and mixing tube, a generator chamber surrounding the lower end of the gallery, a connected generator chamber surrounding the lower end of the mixing tube below said orifices whereby to deflect the sub-flame 90 from said orifices upwardly against the opposed generator chamber, said lower generator connecting with a main jet orifice opening into the lower end of said mixing tube.

2. A burner of the class described comprising a central mixing tube, a gallery surrounding the upper end of said mixing tube and having an opening registering with the open top of said tube, the wall connecting the lower end of said gallery and mixing tube being formed with downwardly directed sub-flame orifices, a generator chamber surrounding the lower end of said gallery, a connected generator chamber surrounding said mixing tube below said sub-flame orifices whereby the sub-flames will strike against the lower generator and be deflected against the upper generator, the lower end of said mixing tube having lateral openings to the outer air and said lower generator being connected with a main jet orifice alining with the bottom of said mixing tube below said lateral openings.

3. A burner of the class described comprising a central mixing tube, a gallery surrounding the upper portion of said mixing tube and spaced therefrom, said burner being formed with downwardly directed sub-flame orifices intermediate of the gallery and mixing tube, a generator chamber surrounding the lower end of the gallery, and an outwardly directed portion surrounding the lower end of the mixing tube below said orifices whereby to deflect the sub-flame from said orifices upwardly against the opposed generator chamber, said generator chamber connecting with a main jet orifice opening into the lower end of said mixing tube.

4. A burner of the class described com-

prising a central mixing tube, a gallery surrounding the upper end of said mixing tube, the top of said mixing tube and gallery being formed with corresponding openings and said burner being formed with downwardly directed sub-flame orifices between said gallery and mixing tube and a main jet orifice below the lower end of said mixing tube, and means for progressively 5 vaporizing hydrocarbon by sub-flames comprising a generator chamber surrounding the lower end of said gallery, a connected generator chamber surrounding the mixing

tube below and inside said outer generator chamber, said lower generator chamber being connected with the main jet orifice and an initial vaporizer supported at the inlet side of the upper generator and projecting below the same to be exposed to the heat of the sub-flame. 15

In testimony whereof I affix my signature in presence of two witnesses.

SIMEON F. PIERCE.
